UNITED STATES PATENT OFFICE.

HENRY DELANO CARRYL, OF NEW YORK, N. Y., ASSIGNOR TO JAMES R. HAY, OF NUTLEY, NEW JERSEY.

PAINTING APPARATUS.

SPECIFICATION forming part of Letters Patent No. 703,385, dated July 1, 1902.

Application filed August 9, 1901. Serial No. 71,433. (No model.)

To all whom it may concern:

Be it known that I, HENRY DELANO CARRYL, a citizen of the United States, and a resident of the borough of Manhattan, city of New York, and State of New York, have invented certain new and useful Improvements in Apparatus for Painting or Cleansing Surfaces, of which the following is a specification.

My invention relates to an apparatus for 10 painting or cleaning all classes of surfaces, and the same is primarily intended to provide a system by means of which paint or any other coloring or any cleaning liquid can be applied automatically to a brush or other painting-tool in such a way as to enable a large surface 15 to be treated with the greatest possible economy of cost and time.

At the present time there is no practicable apparatus in actual use by means of which 20 high buildings, bridges, and other similar structures presenting great areas of surfaces can be successfully and properly painted or cleaned except by means of implements manually operated; and the object of the present 25 invention is to provide a practicable, simple, compact, easily-operated, and reliable mechanism for painting or cleansing large surfaces.

A great many forms of apparatus have here- 30 tofore been devised for spraying or ejecting liquids from a movable nozzle by means of compressed air, and some of them have undertaken to paint by means of a stream of paint forced by compressed air into a brush or else 35 through a spraying-nozzle.

In the case of an ordinary light easily-flowing liquid—such, for example, as is used in the ordinary form of portable garden-sprayers—it is possible to successfully and effec- 40 tually eject the liquid by means of any form of pump which not alone may supply a liquid-tank from which the liquid is ejected, but also which may in itself create the air-pressure. Where, however, a heavy or sluggish 45 material is used, such as paint, which has to be ejected from a dense and more or less homogeneous body, like a brush which constantly divides the stream at a great many points and reduces the pressure, the ordinary 50 form of light spraying device which is found in many forms of garden-sprayers or syringes

will be useless for the reason that a pressure cannot be maintained except for a very short time, and the moment that the pressure falls the tool ceases to be effectual and operation 55 unsuccessful. Again, in all of these forms of apparatus when the apparatus is to be re-filled the chamber has to be opened and the pressure after filling restored, or else the work has to be constantly stopped to pump in air 60 and material together.

I have discovered that where the tank containing the liquid is provided with an independent air-compressing device which is of such construction that by means of it the 65 pressure in the tank may be kept substantially constant without reference to the amount of liquid in the same, and if a pump be provided whereby the tank may be supplied with the liquid to be used in painting 70 from time to time, as may be necessary, it will be possible to produce an apparatus which will enable the heaviest class of liquid to be used in a brush without appreciable loss of pressure in the chamber in which the 75 liquid is stored.

The system which is embodied in the present invention may be briefly characterized as consisting of, first, a portable chamber arranged to contain a suitable painting or 80 cleaning material upon which air-pressure can be constantly exerted, so as to produce an automatic discharge of the material at the will of the operator; second, a flexible tube through which the paint is supplied to the brush or 85 other tool; third, a suitable brush or cleaning-tool which will vary from time to time in form or position, according to the particular surface to which the paint or cleaning liquid is to be applied; fourth, an independent 90 pump or other suitable pressure-creating device whereby the pressure is applied to the liquid in the reservoir; fifth, a device, preferably a pump, for supplying the paint or other fluid to the reservoir either automatic- 95 ally, by gravity, or by hand, and, preferably, sixth, an independent auxiliary air-chamber used to accumulate any liquid that may over- 100 flow from the main chamber and prevent same from entering pressure-gage, and, sev- enth, an arrangement of valves whereby the apparatus and paint-conducting agencies may

from time to time be cleaned out without disturbing the material or pressure in the pressure-chamber.

The invention will be best understood by reference to the accompanying three sheets of drawings, forming a part of this specification, in which—

Figure 1 is a diagrammatic view of the apparatus. Fig. 2 is a vertical elevation of the apparatus, showing its component parts and its method of operation; and Fig. 3 is a plan view of the apparatus.

Similar figures refer to similar parts throughout the several views.

15 In the drawings, 7 represents a pail or other receptacle forming a reservoir in which paint or any other coloring or cleansing medium is contained.

2 2 is a chamber into which the painting or 20 cleansing material is introduced through the pipe 3 by means of a force-pump 4.

5 is a stand upon which the chamber 2 rests, provided with rollers 34 and 34.

6 is a flexible hose of suitable length connecting the chamber 2 with the receptacle 7 in the manner hereinafter described.

Chamber 2 is preferably made of metal and cylindrical, as shown, and is firmly attached to the stand 5 in any convenient manner.

30 The force-pump 4 is attached to the stand 5 by the screws 50 and consists of a piston-rod 10, sliding in the cylinder 4, provided with a piston-head 11, Fig. 1, and is operated by the lever-arms 13, connected by the handle 12.

35 The pipe 3 is connected with the force-pump 4 by the pipe 8, which enters at the bottom of the cylinder below the piston 11, as shown in Fig. 1, and on either side of the point where the pipe 8 connects with the pipe 3 two 40 check-valves 15 and 17 of the ordinary construction are provided. The horizontal pipe 3 is connected with the chamber 2 by means of the pipe 9. This pipe contains an ordinary cut-off valve 16, actuated by the handle 30. One

45 end of the pipe 3 is connected with a hose 6, the other extremity of which hose passes into the receptacle 7. A cut-off valve 14, having a handle 21, is placed in the pipe 3 beyond the point where the pipe 9 connects with it,

50 whereby the flow from the end of the pipe may be controlled. An air-pump 18, with a piston 19, which is generally of similar construction to the force-pump 4, is provided upon the stand 5, placed, preferably, as shown

55 in Fig. 3, at the side of the force-pump 4 and attached to the stand 5 by means of a similar series of screws 51. This is actuated by means of two levers 23, connected by a handle 22. The compressor is shown in the dia-

60 grammatic view, Fig. 1, and by means of it compressed air is caused to enter the upper part of the chamber 2 through the pipes 20 and 38. The pipe 20 contains stop-cock 37, placed at any convenient position for the purposes hereinafter specified. The air-pump is

65 of any convenient type and, as is shown on the right, is operated by ordinary hand-levers

and may be placed at any convenient position upon the stand 5 with reference to the chamber 2. The chamber 2 is closed by a 70 cap 21, screwed into position in any convenient manner. In order to prevent the material entering from the force-pump 4 into the chamber 2 from flowing back into the receptacle 7, the two check-valves 17 and 15 are 75 provided, as shown. When the material enters through the check-valve 17 into the interior of the force-pump, this valve is opened by the movement of the piston 11, this material is forced through the check-valve 15 and 80 thence through the pipe 9 into the chamber 2, and as soon as it passes the check-valve 15 the latter shuts and prevents its return. Any convenient manner of attaching the flexible hose 6 to the pipe 3 may be employed. 85

1 is a brush of any convenient form, which is attached, by means of an adjustable hinge-joint 39, to a handle 24.

25 is a valve by means of which the supply of liquid entering the handle can be regulated. The lower end of the handle 24 is coupled by the union 26 of a flexible hose 27 of any convenient length. The other end of the hose is attached to a pipe 41, emerging from the chamber 2. The flow of liquid from 95 the chamber into the hose 27 is controlled by a valve 28, actuated by a handle 29.

A pressure-gage 60 is provided, which serves to indicate the pressure in the chamber 2, and in order to prevent any paint or cleansing material from entering the pressure-gage and clogging it and preventing it from working satisfactorily it is found convenient to insert a supplemental chamber 61 between the air-compressor 18 and the chamber 2. This consists of an ordinary air-chamber connected at the bottom with the top of the chamber 2 by means of the pipe 38 and provided with an escape-valve 39 at the bottom. The air from the air-compressor 18 enters this by means of 100 the pipe 20, controlled by the check-valve 62 and the cut-off 37. The bottom of chamber 2 is provided with an outlet-valve 64, by which its contents may be drawn off from time to time, if desired. 115

The method of operation is as follows: Paint or other similar coloring or cleansing material is placed in the receptacle 7, and the loose end of the hose 6 is inserted therein. The hand-pump 4 is then put into operation by 120 moving the handle up and down. The valve 16 is opened and the valve 14 is closed, and as a consequence the paint or other material will be forced from the receptacle 7 into the interior of the chamber 2 and gradually rise 125 therein. As soon as a sufficient amount of material has accumulated in the chamber 2 the valve 16 is then closed by turning the handle 30, and the air-compressor 18 is actuated by the handle 22, and as a consequence 130 the air will be compressed in the upper part of the chamber 2, and a pressure of any convenient number of atmospheres will be produced in the interior thereof. This pressure

can be determined by the movement of the finger upon the dial of the pressure-gage 60. When it is desired to apply the paint or other material, the valve 16 is closed and the valve 5 28 is opened by turning the handle 29, and the effect of the pressure in the chamber 2 will be such as to cause the material to flow through the pipe 41 into the flexible hose 27 and automatically and continuously enter 10 through an appropriate tube in the handle 24 of the brush when the valve 25 is opened. This valve may be of any convenient construction, and therefore the position is merely indicated by numeral in Fig. 3. The hose is 15 sufficiently long to enable the operator to take the handle of the brush 24 in his hands and move it to any convenient place and paint any convenient surface without reference to the position of the apparatus upon the stand 20 5. As soon as the pressure in the chamber diminishes to such an extent that the paint no longer flows freely through the brush all that the operator has to do is to close the valve 28 and move the handle 22 of the air-pump 18 a few times, and thus restore the 25 pressure of the chamber 2 to what it originally was. The operator thereupon opens the valve 28, and in this way the operation will be continued until pressure drops again, the 30 control of the flow through the handle being effected, as before, by means of the valve 25. When it is desired to wash out the brush or apparatus, the tube 6 may be withdrawn from the receptacle 7 and placed in a similar 35 receptacle containing water, benzin, naphtha, or any other convenient cleansing substance, which substance may then in similar manner be pumped into the chamber 2 by means of the hand-pump 4 and then forced through 40 the brush, in the same manner as the paint, by means of the compressed air resultant from the operation of the air-pump 18. When it is desired to wash out the brush directly without causing the washing fluid to traverse 45 the chamber 2, the hose 27 may be attached to the coupling 32 at the end of the pipe 3. The valve 16 will then be closed and the valve 14 opened, whereupon the cleansing material will pass directly from the receptacle 50 into the pump 4 and be forced by the operation of the force-pump through the brush, thus thoroughly and expeditiously cleansing the brush, hose 6, and all its various connections, and yet at the same time the 55 liquid in the receptacle 2 and the pressure thereon will remain undisturbed. By opening the valve 64 the contents of the chamber 2 may be from time to time, as may be desired, readily removed.

60 I claim as my invention—

1. In a portable apparatus for painting or cleansing surfaces, the combination of a chamber and a suitable base or stand, a supplemental chamber connected therewith, a receptacle for containing the painting or cleansing material, a pump connected with the principal chamber and arranged to be connected

with the receptacle for introducing the material into the chamber in convenient quantities, an independent air-compressor connected with said supplemental chamber by a suitable pipe for causing the air in the chamber to be compressed and the material to flow automatically therefrom, a portable hand-tool arranged to paint or cleanse, a flexible conducting-hose connecting the chamber with the tool, whereby the painting or cleansing material can be introduced into the tool, and a valve in the handle of the tool for controlling the supply of the material to it through the hose.

2. In a portable apparatus for painting or cleansing surfaces, the combination of a chamber and a suitable base or stand, a receptacle for containing the cleansing or painting material, a pump connected with the chamber and arranged to be connected with the receptacle for introducing the material from the receptacle into the chamber in convenient quantities, an independent air-compressor connected with the chamber by a suitable pipe for causing the air in the chamber to be compressed and the material to automatically flow therefrom, a portable hand-tool arranged to paint or cleanse, a flexible hose of convenient length connecting the chamber with the tool, whereby the painting or cleansing material can be introduced into the tool, a valve in the handle of the tool for controlling the supply of the material to it, and a direct connection between the pump and the tool provided with appropriate valves, whereby the pump, hose and tool may be washed out by means of a liquid introduced by the force-pump without passing through the chamber.

3. In a portable apparatus for painting or cleansing surfaces, the combination of a chamber, and a suitable base or stand, a supplemental chamber connected therewith, for catching any overflow, an independent air-compressor connected with the supplemental chamber for causing the air in both chambers to be compressed and the material to automatically flow from the chamber, a portable hand-tool arranged to paint or cleanse, a flexible conducting-hose connecting the chamber with the tool, whereby the painting or cleansing material can be introduced into the tool, a valve in the handle of the tool for controlling the supply of the material to it, a pump for forcing liquid into the chamber and a direct connection between the pump and the tool provided with appropriate valves whereby the pump, hose and tool may be washed out by means of a liquid introduced by the pump without passing through the chamber.

4. In a portable apparatus for painting or cleansing surfaces, the combination of a closed chamber; a receptacle for containing the cleansing or painting material; a pump connected with the chamber and arranged to be connected with the receptacle by a flexible tube or hose for introducing the material from the receptacle into the chamber in convenient

quantities; an air-compressor connected with chamber by a suitable pipe for causing the air in the chamber to be compressed and the material to automatically flow therefrom; a 5 gage for indicating the pressure in the chamber; a portable hand-tool arranged to paint or cleanse; a flexible hose of convenient length connecting the closed chamber with the tool, whereby the paint or cleansing material can be introduced into the same; a 10 valve in the handle of the tool for controlling the supply of the material to it; a pipe connecting the pump and the tool; appropriate

valves placed therein by opening and closing which, the pump, hose and tool may be washed 15 out by a liquid introduced by the pump without passing through the chamber.

In testimony that I claim the foregoing as my invention I have signed my name, in presence of two witnesses, this 8th day of August, 20 1901.

HENRY DELANO CARRYL.
